UNITED STATES PATENT OFFICE.

JOHN P. CLUETT, OF NEW YORK, N. Y.

DESIGN FOR BOX.

Application filed May 23, 1925. Serial No. 13,542. Term of patent 3½ years.

To all whom it may concern:

Be it known that I, JOHN P. CLUETT, a citizen of the United States, residing at 920 Riverside Drive, New York city, New York, have invented a new, original, and ornamental Design for Boxes, of which the following is a specification, reference being had to the accompanying drawing, forming part thereof.

In the drawing, the figure is a perspective view of a box.

I claim:

The ornamental design for box, as shown.

JOHN P. CLUETT.
